FOREIGN PATENT DOCUMENTS

WO 2012110453 A1 8/2012

Primary Examiner — Darlington Ly

(74) Attorney, Agent, or Firm — Scott B. Markow

(57) **CLAIM**

The ornamental design for a tool bit for driving threaded fasteners, as shown and described.

DESCRIPTION

FIG. 1 is a perspective view of a tool bit for driving threaded fasteners showing our new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a rear elevation view thereof; and,

FIG. 7 is a front elevation view thereof.

The broken lines in the drawings illustrate portions of the tool bit for driving threaded fasteners that form no part of the claimed design.

1 Claim, 4 Drawing Sheets
